UNITED STATES PATENT OFFICE.

FRANK A. GRUNOW, OF NEW ORLEANS, LOUISIANA.

WATER-ELEVATOR.

No. 901,238.

Specification of Letters Patent.

Patented Oct. 13, 1908.

Application filed January 17, 1908. Serial No. 411,319.

To all whom it may concern:

Be it known that I, FRANK A. GRUNOW, a citizen of the United States, residing at New Orleans, in the parish of Orleans and State 5 of Louisiana, have invented new and useful Improvements in Water-Elevators, of which the following is a specification.

This invention relates to an anti-friction water elevator, or pumping apparatus, provided with a running wheel comprising a central hub, an outer annular ring, arms connecting same with the hub, and a series of water-cutting and expelling blades connected with the aforesaid annular ring on lines tangential with the inner circle thereof and projecting from the said annular ring, preferably in parallel lines with the driving shaft; or the said blades may be inclined either to, or from the shaft, or in the direction of travel, if desired so that the lower ends being in advance shall have a plowing or lifting effect upon the water. The outer projecting ends, or heels, of the cutting blades are connected with an annular ring, 25 by which greater strength and stability is insured to same. This ring, however, may be omitted when the apparatus is designed for very light work, but in such cases only.

The apparatus is provided with an annular base and a dome-shaped cover, the latter supported above the base by stands of peculiar form and bolts passing therethrough.

The invention further consists in certain details of construction and combinations of parts, as shown in drawings and hereinafter fully described and specifically claimed.

Referring to the drawings—Figure 1 is an elevation of the apparatus, one-half of which is shown in section. Fig. 2 is a top view of one-half of the apparatus, and a transverse horizontal section of the other half thereof. Fig. 3 is a view from the underside of the running wheel or piston. Fig. 4 represents the underside of a gland or stuffing box cover. Fig. 5 is a section view, representing the underside of a portion of the base of the apparatus. Fig. 6 is a vertical section of the pumping apparatus with its driving shaft and pulley, as arranged in a vertical flume or penstock. Fig. 7 represents the pumping apparatus within a decked penstock, the latter shown as being provided, at one side, with an iron discharge pipe, and the other side with a wooden vertical flume; in practice, 55 however, either the pipe or flume is dispensed with, depending upon the use to which the

apparatus is to be applied. Fig. 8 shows a simplified form of pumping apparatus and flume. Fig. 9 represents the apparatus arranged within a substantial structure, for 60 drainage and other purposes, where a large body of water is to be raised and discharged.

The numeral 1 designates the lower part of the apparatus, which is of cylindrical form and provided with an inwardly and outwardly projecting top flange 2 and a series of downwardly projecting guides 3 to receive the ends of an adjustable frame 4, the center of which is provided with a steel step 5 to receive the lower end of the driving shaft 6. 70 The frame 4, carrying the steel step 5 and driving shaft 6, is supported and vertically adjusted by screw-threaded rods 7 and nuts 8; the lower ends of the rods 7 being bent in stirrup form to fit the groove and perforated ends of the frame 4, in which position they are secured by the nuts 9.

To support the adjustable frame 4, when in its lowermost position, each end thereof is fitted within a link 10, the upper part of 80 which is connected with the guides 3, as shown in Figs. 1 and 4.

A series of deflecting stands 11, comprising plates having curved surfaces terminating in sharp edges and provided between 85 said edges with a vertical hole for the reception of one of the rods 7, are arranged around the top flange 2 of the lower part of the apparatus for the support of the dome or cover 12, which is likewise provided with 90 bolt holes for the rods 7 so as to be secured thereon by the nuts 8. These stands are arranged on the flange 2 at an angle of about forty-five degrees to a radial line, as shown at Fig. 2, to deviate the outward flow of 95 water, and thus relieve the wheel of pressure, taking advantage of current and gyration or swirl of the water, forming a suction around the periphery of the wheel whereby the efficiency of the apparatus is greatly increased.

The inside, or under surface of the cover 12, is provided with two concentric ribs or flanges 13, 14, against which the top of the running wheel 15 operates, as shown in Fig. 1. The said running wheel is preferably made of a slightly dished annular ring 25 having an upwardly and inwardly inclined rim 26 and curved arms 27, connecting same with a central hub 28, the latter adapted to be keyed or otherwise secured to 100 the driving-shaft 6, of the apparatus.

A feature of the invention consists in pro-

viding the edges of the aforesaid curved arms 27, with oppositely inclined sharp edges; the advance or convex edge of each arm being sharp along its upper edge *a*, 5 while the rear or concave edge of each arm is sharp at its lower edge *b*; thus the said arms have a propeller-like action on the water, cutting and forcing the same downward and outward between the blades of the 10 wheel; the tendency being to raise the wheel and thereby lessen the friction on the bearings of its shaft as well as to prevent any outflow of water over the annular ring 25 and its inner rim 26.

15 The letter *c* designates a series of water-cutting and expelling blades, which are cast or otherwise secured tangentially to the inner circle of the annular ring 25 of the running wheel and project therefrom in parallel 20 lines with the driving shaft 6, or in line slightly inclined to or from same. Except in machines, adapted for very light work, the outer extremities of the cutting blades *c* are connected with an annular ring *f*, which 25 is adapted to operate on the inner flange 2 of the lower part of the apparatus, and within the feet or base of the deflecting stands 11 thereof. The blades *c* are made with straight flat surfaces, slightly tapered in- 30 wardly to present a sharp cutting edge *d*, and with slightly rearwardly curved heels *e*, to facilitate the outward discharge of the water. The top of the cover 12 is provided with a cylindrical section 16, having an outwardly projecting flange 17 to permit of its 35 being bolted to a decked flume or penstock. The cylindrical projection 16 is also provided with a vertical opening 18 having a seat in the lower part thereof, upon which a ball-valve 19 is fitted, so as to permit of the 40 escape of air when the machine is submerged. A stuffing box 20 is formed in the center of the top of the cover 12, and a vertically divided cover 21 is adapted to fit 45 therein, to take the wear of the driving shaft. The said stuffing box cover is secured in position by screw-threaded bolts 22, so as to permit of the packing being tightened when necessary.

50 Collars 23 and 24 are fitted to the upper and lower parts of the driving shaft 6 to relieve the step 5 and stuffing box cover 21 of the weight of the said shaft and the running wheel thereon. The lower collar also serves 55 to exclude sand and grit from the step bearing, and thus it protects same from excessive wear.

The apparatus is secured within the lower part of a flume or penstock by bolts passing 60 through the flange 2 and the timbers upon which it rests, as shown in Figs. 6 and 9; or, when applied within a decked penstock, by bolts passing through the flanged portion 17 of the cover 12 of the apparatus, and the 65 floor or timbers upon which it rests.

In the modified form of apparatus shown in Fig. 8 the deflecting stands 11 are bolted to timbers in the lower part of the flume, the driving shaft 6 being extended to the step 5 which is secured to the lower part of the 70 flume frame. In this instance, no provision is made for adjusting the shaft and its running wheel.

As heretofore stated, the form of apparatus shown in Fig. 8 is only employed for 75 light work, while at Fig. 9 the apparatus and structure surrounding same is of the most substantial character.

In operation, the water enters through the bottom of the apparatus wherein it is sliced or plowed by the cutting blades of the running wheel, and centrifugally thrown off the periphery of the wheel into the flume or penstock. The continuous motion of the said wheel forces the water upward, where it is discharged through the outlet provided therefor, as shown in the various figures. The velocity of the discharge is in perfect 85 harmony with the speed at which the skirt of the wheel moves; that is, were there no 90 back pressure or outside thrust against the revolving knives, but as there is a weight in true proportion to the head of the column, the speed of the skirt of periphery must be increased fast enough to perfectly sustain 95 this given head or column of water and keep it stationary at this level. Again, to this skirt speed must be added the velocity with which it is desired to discharge the water from the wheel, in order to make up for a 100 given pumping capacity for practical work.

Having now described my invention, what I claim as new and desire to secure by Letters Patent is:—

1. The combination in a running-wheel for 105 water-elevators, of an annular ring, a central hub and curved arms connecting the ring and hub, the convex side of each arm being sharp along its upper edge and the concave side sharp at its lower edge, and water-cutting and expelling blades connected with the annular ring and projecting therefrom in lines preferably parallel with the driving shaft of the wheel, and tangential to the inner circle of the ring. 110

2. The combination in a running-wheel for 115 water-elevators, of an annular ring, a central hub and curved arms connecting the ring and hub, the convex side of each arm being sharp along its upper edge and the concave side sharp at its lower edge, a series of cutting blades connected with the annular ring and projecting therefrom in lines preferably parallel with the driving shaft, the said cutting blades having flat surfaces tapered in- 120 wardly to a sharp cutting edge, and tangential to the inner circle of the ring, the outer ends of the blades being rearwardly curved and having their outer corners connected with an annular ring, as set forth. 125

3. The combination in a water-elevator having a dome-shaped cover provided at its top with a vertical opening having a valve seat therein and a ball valve adapted to 5 operate thereon, a stuffing box and a vertically divided cover therefor; a driving shaft and a running-wheel comprising a central hub, an annular ring and curved arms connecting the hub and rim, with water- 10 cutting and expelling blades projecting from the annular ring, as set forth.

4. In a water elevator, the combination of a lower cylindrical section having an open bottom and a flanged top, said section being 15 provided with a series of vertical guides; a series of deflectors supported upon the flanged top of the cylindrical section, each deflector having curved surfaces terminating in sharp edges and provided with a rod-

hole, as described, a dome-shaped cover 20 mounted upon the deflectors and provided at its apex with a stuffing-box, having an opening in which is seated a valve; rods vertically movable in the deflectors; a frame movable in said guide and attached to the 25 lower ends of said rods and a step connected with the center of said frame; a vertical shaft journaled in the stuffing-box and step; a running-wheel provided with water-cutting blades mounted on the shaft, and means 30 for elevating and adjusting the position of the frame and wheel.

In testimony whereof I affix my signature in presence of two witnesses.
